United States Patent Office.

CHARLES BINZER, OF NEW YORK, N. Y.

Design No. 2,951, dated March 17, 1868.

DESIGN FOR A LAMP-SHADE.

The Schedule referred to in these Letters Patent and making part of the same.

TO ALL WHOM IT MAY CONCERN:

Be it known that I, CHARLES BINZER, of the city, county, and State of New York, have invented a new and improved Design for Lamp-Shades; and I do hereby declare that the following is a full, clear, and exact description of the same, reference being had to the accompanying drawings making a portion of this specification, in which—

Figure 1 is a side view of a lamp-shape, made according to my design.

Figure 2 is a plan view of the same.

Similar letters of reference indicate corresponding parts in both figures.

The ring or annular band at the top of the shade is shown at A, and is formed externally with an annular groove or depression, a', represented in fig. 1. That portion of the shade immediately below the ring A is formed on the frustum of a cone, as shown at a b, and the lower portion of the shade is formed upon the frustum of another cone, the sides b c of which are more nearly vertical than those, a b, of the other or upper portion just mentioned, and the bottom of which is scalloped, as indicated at b, in fig. 1, so that that portion of the shade below the ring A may be said to be formed of two frusta, having sides of different inclinations, and the lower one of which is scalloped at its edge.

What I claim as my invention, and desire to secure by Letters Patent, is—

The design for a lamp-shade, substantially as herein described, and represented in the accompanying drawings.

C. BINZER.
